FOUNDATION GARMENT

Katherine E. Cunningham, New Haven, Conn.,
assignor to I. Newman & Sons, Inc., New
Haven, Conn., a corporation of Connecticut

Application November 23, 1933, Serial No. 699,462

7 Claims. (Cl. 2—30)

This invention relates to foundation garments, and has for an object to provide an improved construction wherein a constricting under vest is presented with either a wrap-around or step-in body structure.

Another object of the present invention is to provide a foundation garment having a constricting under vest structure extending substantially from the top to the bottom thereof at the front and lacing at the front using eyelets to provide a final adjustment.

A further object of the invention is to provide a foundation garment having a body with a vest structure and means for adjusting the body to take the strain from the vest structure, together with a brassière formation connected to the back portion of the body and presenting at the front means for supporting and uplifting the breasts and also presenting a constricting belt to hold the upper part of the body of the garment in position to more or less constrict the parts of the body of the wearer adjacent the diaphragm.

In the accompanying drawing—

Figure 1 is a perspective view of a garment disclosing an embodiment of the invention, the same being illustrated on a figure as it would appear when in use;

Figure 2 is a front view of the garment shown in Figure 1 with the brassière shown open and the front part of the body shown open;

Figure 3 is a rear view of the structure shown in Figure 2;

Figure 4 is a view similar to Figure 1 but showing a slightly modified construction;

Figure 5 is a front view spread out of the garment shown in Figure 4, the same illustrating how disengageable fasteners may be used from top to bottom of the garment instead of the sliding fastener shown in Figure 1.

Referring to the accompanying drawing by numerals, 1 indicates a body which may be termed the corset member, and 2 indicates the brassière. The body 1 may be made of any desired shape but closed at all points except at the front where it has rows of eyelets 3 and 4 for the reception of lacing 5.

The lacing 5 is always in place but is usually loosened before removing the garment or before applying the same. At one side of the lacing 5 is an opening normally closed by a slide fastener 6, said fastener extending from the top of the garment downwardly any desired distance, for instance, to a point near the lower edge, as shown in Fig. 1. Arranged beneath the front sections 7 and 8 is a vest structure 9 stitched to the body

1 and consisting of a plurality of diagonally positioned elastics 10 and 11 and pockets 12 and 13. The pockets 12 and 13 are preferably provided with stiffening steels, though this is not essential. At the upper end of the vest 9 are elastic members 14 and 15 which extend circumferentially instead of diagonally, as is true of members 10 and 11. The diagonal formation of these members assist in constricting the lower part of the body so as to somewhat raise and mold the same whereby the body will be rounded and uniformly shaped. As illustrated in Figure 1 the body 1 of the garment extends over the hips appreciably and, consequently, not only constricts the lower part of the front of the body but the hips also. Preferably the body of the garment extends up to and slightly across the waistline of the person wearing the garment so that the lower part of the brassière 16 may act as a belt for holding in the upper part of the body 1, and also for more or less constricting the body of the wearer at or adjacent the diaphragm. As there is no adjustment of the belt section 16, gores 17 and 18 are provided in the belt section, said gores extending from the bottom of the brassière to the breast pockets, and as these are formed of elastic material stretchable circumferentially there will be produced a tension on the belt section 16 when the disengageable fasteners 19 are secured together.

The disengageable fasteners 19 may be hooks and eyes, snap fasteners, or other connecting means. Suitable straps 20 and 21 are connected to the highest point of the breast pockets and extend over the shoulders and are connected to the extension 22 of body 1, said extension being really part of the body 1 as the various pockets or reinforcing members 23 extend downwardly to the bottom of the body. If desired, stiffening members could be arranged in the pockets 23. The free portions 2' and 2'' of the brassière 2 are connected to the corset body 1 preferably along the seams securing the side pockets 22 in place, thus providing a short free section 2'' and a long free section 2' with fasteners 19 arranged under one of the arms.

As illustrated in Figure 2, the under edges of the sections 2' and 2'' extend a short distance over the body 1, this overlapping permitting the belt structure 16 of the brassière 2 to constrict and hold against bulging the upper part of the body. In order to assist in providing a snug fit to the upper edge of the body 1, elastic sections 24 and 25 are provided at the sides and upper edge. Also, V-shaped gores 26, 27 and 28 are

formed in the corset body, one of these gores being at the top and center of the back and the other two at the bottom on each side of the pack panel 29 which merges into the extension 22. 5 Suitable hose supporters are also provided, two of these supporters, namely, supporters 30 and 31 having one end connected to the lower ends of the pockets 12 and 13 and the other end connected to the lower part of the sections 7 and 8. 10 By this arrangement the vest 9 and associated parts may be prevented from riding up or shifting in an upward direction. If desired, the hose supporters could be connected to the vest structure 9 only, though the arrangement as shown in 15 Figure 2 is preferable.

In Figures 4 and 5 a slightly modified structure is disclosed, wherein the slide fastener is eliminated and the body 1 is open from top to bottom, said opening being in line with the edge of the 20 flap or extension 2". Suitable hooks and eyes or other disengageable fasteners 32 are provided so that this side opening may be connected together. At the front laces 5 are used in connection with the rows of eyelets 3 and 4. When 25 this form of foundation garment is to be used the lacing 5 is loosened sufficiently to cause the sections 7 and 8 to be completely loose. The body 1 which is passed over the body of the wearer is pulled until the fasteners 32 are connected. This 30 will bring the elastic vest structure 9 under tension. The body 1 may then be adjusted to the proper position, and after this has been done the lacing 5 is tightened until the desired tension is secured. The brassière 2 is then fastened as 35 shown in Figure 4 and finally the hose supporters are connected to the hose. In this form of the invention the vest 9 must be stretched by the hands of the person placing the garment on the body. In the form shown in Figure 2 a step-in 40 structure is provided wherein a slide fastener 6 is used to secure tension on the vest 9. When this slide fastener is open and the lacing 5 is loose the wearer may readily pull the garment over the feet and upwardly to the correct position 45 on the body without bringing the vest 9 under very much tension. However, as soon as the slide fastener 6 has been operated to draw the parts together as shown in Figure 1, the vest 9 will be brought under tension. After this has 50 been done the body is adjusted to the proper position and then the lacing 5 tightened to the desired extent, after which the brassière is fastened in place. In fastening the brassière in place it will be seen that the lower edge or that part forming the belt structure 16 will press against the upper edge of the body 1 holding the same in proper position, and will also by reason of the elastic members 17 and 18 act as a constricting belt to hold the body in a rounder or molded 55 position at and above the waist-line.

I claim:

1. A foundation garment of the character described including a corset body open at the front, lacing for drawing said opening together, an 60 elastic vest arranged beneath the front portion of the corset body and extending across said opening, said body having a second opening extending from the top downwardly, and a slide fastener for drawing said second opening together and bringing said elastic vest under tension, said lacing acting to pull the corset body to relieve said tension.

2. A foundation garment including a corset body formed as a step-in, said corset body having 75 an opening at the front with a flap section on

either side of the opening, a resilient vest having its respective edges connected to the corset body substantially at the point where said flaps join said corset body, said flaps and said vest structure being of substantially the same width, means carried by the corset body for stretching said vest after the corset body has been placed in position on the wearer, and lacing carried by the edge portions of said flaps, said lacing acting to draw the flaps towards each other and thereby relieve 10 the tension on said vest structure.

3. A foundation garment including a corset body having an opening in the front, a projection at the back extending above the remaining part of the corset body, an elastic vest spanning said opening, said vest acting continually as a unit, lacing for drawing said opening together, and a brassière formed as a pair of flaps one connected to the corset body at each edge of said projection, one of said flaps presenting a lower elastic section positioned to overlap the upper part of the corset body and acting to hold the upper edge of the corset body in place and produce a molding of the body at a point above the waistline, said last mentioned flap including a pair of breast pockets and an elastic gore for each breast pocket extending from the lower edge of the flap upwardly to the breast pocket, and means for connecting the free edges of said flaps together, said means being positioned to maintain said elastic gores under tension when the garment is in use.

4. A foundation garment including a corset body and a brassière, said brassière merging into the corset body at the back and having a short flap and a long flap, said long flap being provided with a pair of breast pockets and an inelastic body, said long flap being divided at two points, said points of division extending from the respective breast pockets to the bottom of the brassière an elastic gore arranged at each point of division, said gores extending from the lower edge of the brassière up to the breast pockets, whereby a circumferential tension is given to the corset from the breast pockets downwardly, and disengageable means for fastening the two flaps of the brassière together.

5. A foundation garment comprising a corset body having a rear panel, side and front panels, said rear panel projecting above the remaining panels, a pair of circumferentially disposed members connected to said rear panel at the respective edges thereof near the top, said circumferential members forming a brassière, one of said circumferential members being provided with a pair of elastic sections, and breast pockets arranged above the elastic sections and disengageable fastening means for connecting said circumferentially disposed members so that said elastic sections will be under tension.

6. In a garment of the character described, a structure acting as a brassière divided at one point from top to bottom, disengageable fastening means for connecting said points together, said brassière being formed with a pair of breast pockets in the upper half and the lower half being formed with a pair of elastic gores elastic circumferentially, and with inelastic members on each side whereby a constricting belt structure is presented below the breast pockets for constricting the body of the wearer at a point above the waistline without interfering with the brassière said disengageable fastening means being positioned to cause said elastic gores to be continually under tension when the garment is in use.

7. A foundation garment comprising a corset

body and a brassière, said corset body having a pair of front panels, a pair of side sections and a rear section, said rear section extending above the front panels and side sections, an elastic vest connected with the side sections substantially at the same line of connection as the front panels, each of said front panels having a free edge provided with a row of eyelets, and lacing extending through said eyelets for drawing said front panels together, said brassière having a long and a short portion, said long portion having a pair of spaced breast pockets in the upper part and an elastic gore extending from each of the breast pockets to the lower edge of the brassière, and means for disengageably connecting said long and short portions said last mentioned means being positioned to maintain said gores under tension when the garment is in use. 5
